UNITED STATES PATENT OFFICE.

LEROY G. GATES, OF BAKERSFIELD, CALIFORNIA.

ROTARY DRILL BIT.

Application filed July 16, 1923. Serial No. 651,758.

To all whom it may concern:

Be it known that I, LEROY G. GATES, a citizen of the United States, residing at Bakersfield, in the county of Kern and State 5 of California, have invented certain new and useful Improvements in Rotary Drill Bits, of which the following is a specification.

My invention relates to rotary bits for 10 drilling wells.

The objects of my invention are to provide a rotary drill bit which may be operated successfully at high speeds, and which will retain a sharp and effective cutting face 15 throughout the entire life of the bit. A further object is to provide a drill bit which is adapted for removing a section or sections of core from the well, to permit examination at the surface, of the formation in which 20 the bit is working.

My improved drill bit is capable of efficient operation at speeds of 250 revolutions per minute and higher, which is the maximum speed which is at present being attempted, and is therefore particularly adapted for direct connection with an electric motor located above ground, or with an electric or fluid operated motor located in the well immediately above the bit and 25 suspended by a stationary drill stem. On account of the form of my bit, it can be used at the high speeds referred to with a circulating mud fluid, without expending unnecessary power in whirling or churning 30 the mud.

The form and construction of my drill bit may be varied considerably from that shown in the accompanying drawings and hereinafter described, without departing 40 from the spirit of the invention as expressed in the claims hereto appended.

With this in view, a preferred embodiment of my invention will now be fully described with reference to the accompanying 45 drawings, wherein:—

Fig. 1 is a part sectional perspective view of my improved rotary drill bit.

Fig. 2 is a transverse section of the same, taken on the line 2—2 of Fig. 1.

In the drawings, the reference numeral 1 50 designates the outermost of a plurality of cylindrical shells which form the body of the drill bit the inner shells being designated by 1' and 1" respectively, and 2 is a shank 55 for connecting said shells to the drill stem or motor shaft. Said shank is provided

with a central bore 3, which extends to the interior of the shell 1", as shown in Fig. 1, for the purpose of conducting mud fluid thereto. It is to be understood that the 60 lower or discharge end of the bore 3 may assume any desired form, in order to direct the issuing mud fluid in the desired manner.

Each of the shells is provided with a plurality of perforations 4, which may have 65 various desired shapes and positions. These perforations not only provide means of escape for the mud fluid, but also provide a notched or serrated lower edge for the drill body, as shown at 4' which constitutes 70 the cutting face of the bit. This cutting face, moreover, remains notched or serrated, and therefore effective, throughout the life of the bit, because as said face wears away, 75 fresh perforations are intercepted, and each such intercepted perforation forms a new notch in said cutting face.

Each of the shells is provided, both exteriorly and interiorly, with lateral projections, which may be of any desired form 80 and formed with or secured to said shells in any suitable manner. In the drawings these lateral projections are shown as helically directed ribs 5, formed integrally with the shells, and are for the purpose of providing 85 sufficient clearance between the shells and the bore and cores in which they are rotating, to prevent binding.

The shells may be provided interiorly with suitably formed transverse cutters 6, for 90 cutting and breaking up the core formed within each of said shells by its downward boring into the formation. If desired, the transverse core cutters 6 may be omitted or removed, and any well known form of core 95 lifter, not shown in the drawings, may be used in connection with the drill bit in the usual manner, for the purpose of removing entire sections of the core for examination. This process is well known in the art of 100 well drilling, and is referred to herein merely to emphasize the adaptability of my drill bit to such core taking.

It is to be noted that, on account of the cylindrical construction of my drill bit and 105 its plurality of shells, the bit is well adapted for working in hard formation, no power is wasted in churning or whirling the mud fluid and cuttings carried thereby, and on account of the laterally projecting clearance 110 ribs 5, the friction between the non-cutting portions of the bit and the sides of the bore

is reduced to a minimum. Thus my drill bit is capable of efficient operation at speeds considerably in excess of those now employed. Moreover, on account of the perforations 4, the cutting edge or edges of the bit remain effective until the entire bit is worn away.

I claim:

10. A rotary drill bit comprising a plurality of spaced substantially cylindrical concentric shells, each having a cutting face and each shell having a plurality of perforations in its wall.
15. A rotary drill bit comprising a plurality of spaced substantially cylindrical concentric shells, each having a cutting face formed at one end and each shell having a plurality of perforations in its wall; and lateral projections extending from the surfaces of each shell.
20. A rotary drill bit comprising a plurality of connected substantially cylindrical concentric shells, each having a cutting face and each shell having a plurality of perforations in its wall; and transverse core
25. A rotary drill bit comprising a plurality of connected substantially cylindrical concentric shells, each having a cutting face and each shell having a plurality of perforations in its wall; and transverse core

cutters carried by and between the shells.

4. A rotary drill bit comprising a plurality of connected substantially cylindrical concentric shells, each having a cutting face formed at one end, and each shell having a plurality of perforations in its wall; lateral projections extending from the surfaces of each shell; and transverse core cutters carried by and between the shells.

5. A rotary drill bit comprising a plurality of substantially cylindrical concentric shells, connected together at their upper ends and spaced apart at their lower ends, each shell having a cutting face at its lower end and a plurality of perforations in its wall.

6. A rotary drill bit comprising a plurality of substantially cylindrical concentric shells spaced apart at their lower ends, the upper end portions of all said shells being integral, and each shell having a cutting face at its lower end and a plurality of apertures in its wall.

In testimony whereof I have signed my name to this specification.

LEROY G. GATES.
